UNITED STATES PATENT OFFICE.

LESLIE C. ORRELL, OF CHICAGO, ILLINOIS.

FUSE-PLUG.

SPECIFICATION forming part of Letters Patent No. 617,765, dated January 17, 1899.

Application filed September 25, 1897. Serial No. 652,948. (No model.)

To all whom it may concern:

Be it known that I, LESLIE C. ORRELL, of Chicago, in the county of Cook and State of Illinois, have invented certain new and useful Improvements in Fuse-Plugs; and I do hereby declare that the following is a full, clear, and exact description thereof, reference being had to the accompanying drawings, and to the letters of reference marked thereon, which form a part of this specification.

This invention relates to improvements in automatic cut-outs for electric circuits, and refers more specifically to that class of such cut-outs comprising a cylindric body or plug provided with means for detachably securing a fuse-wire thereto and which is adapted for use with a base or block having a socket with which said plug has screw-threaded connection.

The object of the invention is to provide an improved device of this character in which the fuse-wire may be readily and easily attached to and detached from the plug, so that when said wire has been fused by an excessive current passing therethrough it may be removed from the plug and a new one inserted in lieu thereof without the necessity of discarding the entire plug, as has heretofore been common.

Another object of the invention is to provide an improvement whereby the fusing of the wire will not tend to render inoperative the parts of the device for clamping the ends of the wire.

The invention consists in the matters hereinafter set forth, and more particularly pointed out in the appended claims.

In the drawings, Figure 1 is a face view of two fuse-plugs and a fuse-block made in accordance with my invention. Fig. 2 is a side or edge view thereof. Fig. 3 is a detail top or face view of one of the fuse-plugs with its cap removed. Figs. 4 and 5 are sectional views taken on the lines 4 4 and 5 5, respectively, of said Fig. 3. Fig. 6 is a perspective view of one of the clamping devices for the fuse-wire. Fig. 7 is a cross-section taken on lines 7 7 of Fig. 5. Fig. 8 is a detail cross-section taken on line 8 8 of Fig. 1.

A fuse-plug made in accordance with my invention consists in its main features of a

solid body of insulating material of suitable form adapted for detachable connection with a fuse block or base and provided with two recesses, within which are located clamping devices which engage the opposite ends of the fuse-wire and by which said wire is held in place. Said plug is provided with means for holding the clamping devices in place, and said clamping devices are electrically connected through the plug and the holding-block with the opposite terminals of the line-wire in any usual or preferred manner.

My invention is herein shown as embodied in a plug A, which is of ordinary construction so far as its general shape is concerned. Said plug is reduced in diameter in its lower end to fit within a socket in a base or block B, of usual construction, with which the socket has screw-threaded connection. Said reduced portion is provided with an exterior metallic cover or sheath A', upon which are formed exterior screw-threads and which serves as a portion of the metallic connection between one end of the fuse-wire and one terminal of the line-wire, as will herein-after more fully appear. The plug is provided on its upper end with a cap A², which incloses the same and the operative parts mounted thereon, said cap fitting over the outer circumference of the plug and having screw-threaded connection therewith. Said body portion of the plug will be made of any suitable insulating material, such as glass, porcelain, or the like.

Within the upper or enlarged part of the plug and adjacent to the periphery, on one side thereof, are formed two recesses or depressions a a, which open at the upper face thereof, and within each of which is mounted a clamping device C, to which the opposite ends of a fuse-wire D are attached, as shown more clearly in the plan view, Fig. 3. Said recesses and the holding devices mounted therein are of oblong rectangular shape as seen in plan view and are arranged obliquely with respect to each other or with the parts thereof adjacent to the center of the plug at a greater distance apart than the opposite sides of the same. Said clamping devices are generally similar in their construction and mode of operation to the clamping devices shown and described in my prior pat-

ent, No. 542,713, dated July 16, 1895, and are made as follows: The main frame or body portion of each of said clamping devices consists of a base-plate, which rests on the bottom of the recess a , and a guide-plate C^2 , arranged at right angles to the base-plate and of a length approximately equal to the depth of the recess and adapted to rest against one of the side faces thereof. Said guide-plate C^2 is provided on the opposite edges thereof between its ends with integral guide-arms C^3 , which are bent to form guides and which serve to hold in place and guide the movable portion of the device. Said movable part of the device consists of a shank C^4 of less width than the guide-plate C^2 , which engages the latter and is embraced by the guide-arms C^3 , and a clamping-plate C^5 , which is arranged at right angles with the shank C^4 and parallel with the plane of the base-plate C^1 of the stationary frame.

C^6 designates a guide-pin which is mounted at its inner end in the base-plate of the stationary part of the device and extends at its outer end through a guide-aperture in the clamping-plate C^5 . Said guide-pin is provided in its upper end above the plate C^5 with a clamping-head C^6 , which is parallel with the clamping-plate C^5 and coacts with the upper face thereof to clamp and hold the fuse-wire. The movable part of the device is held yielding against the clamping-head by means of a suitably-applied spring C^7 , which, as herein shown, is arranged spirally around the pin C^6 and is engaged at its opposite ends with the base-plate C^1 and the clamping-plate C^5 .

When it is desired to detach the adjacent end of the wire D , the movable part of the device will be depressed or thrust inwardly, and the wire may then be withdrawn and a new wire substituted, after which the pressure will be relieved and the movable part of the device restored to its place under the action of the spring.

One of the clamping devices—the one shown at the left-hand side in Fig. 1—is electrically connected with a contact plate or bottom E , mounted centrally in the lower end of the plug, by means of a connecting-strip E' . Said strip E' is herein shown and will preferably be made an integral part of the base portion C^1 of the clamping device. As herein shown, said strip is joined to the plate C^1 at the inner corner thereof, or that adjacent to the center of the plug, and thence carried downwardly through an oblique opening a' in the body of the plug to the contact device E . Said strip will conveniently be carried at its lower end slightly beyond the lower face of the plug, and the extreme end will be bent at an angle thereto or parallel with the central longitudinal axis of the plug. The contact-plate will be provided centrally with an aperture which said extreme end of the strip engages and by means of which said contact-point may be secured to the strip and in place by soldering or otherwise. Said contact-

plate is adapted to engage the terminal B' in the socket of the block B , which terminal is connected with the line-wire in a manner usual in such constructions, said line-wire being attached to a binding-post B^2 , which has metallic connection with the terminal B' in the bottom of the socket, with which the central contact-plate E has engagement, when said plug is in place in the socket.

The clamping-strip which engages the opposite end of the fuse-wire is of a construction like that last described, with the exception that said first-mentioned device is electrically connected with the exterior covering or sheath A' of the reduced portion of the plug, as clearly shown in Fig. 8. The lower or horizontal portion of the stationary part of the clamping device is shown as provided with a short integral connecting-strip E' , Fig. 8, which is attached to the inner end of said device with respect to the center of the plug and is carried downwardly through and is connected at its lower end with the upper edge of said metallic sheath, being preferably connected thereto by soldering or like means. The line-wire will be connected with the last-mentioned holding device of the plug through the medium of a ring B^3 , which is screw-threaded to receive the outer covering or sheath A' of the reduced portion of the plug, said ring being in metallic connection with a binding-post B^4 on the block in a familiar manner. Said clamping devices are herein shown as held in place within the recesses of the plug both by the attachment of the connecting-strips with the exterior contact plates or pieces and also by means of holding-screws F , which pass through radial openings in the sides of the plug and engage the outer faces of the holding devices. As herein shown, the inner ends of said screws are reduced and provided with screw-threads which engage interiorly-screw-threaded apertures in the guide-plates C^2 of said holding devices. The use of such screws or other special retaining means is not, however, essential, it being obvious that the holding devices will be sufficiently retained in place for most purposes by the attachment of the connecting-strips thereof with the exterior covering A and the contact-plate E , as before set forth.

A solid cylindric plug of insulating material provided with recesses for holding devices constructed to detachably hold the fuse-wire is a great improvement over such fuse-plugs as heretofore in common use. The cylindric screw-plugs now in common use are provided with a fuse-wire or strip which is permanently embedded in the same, so that when said wire becomes fused or burned out the plug must either be thrown away entirely or refitted with a fuse-wire by one who is skilled in such work. The common practice, as it has come under my observation, is to throw away burned-out plugs and not attempt to renew the fuse-wires. With my construction, on the other hand, these plugs may be

used indefinitely, it only being required when a fuse has been burned out to replace the fuse-wire, and this can be done easily and quickly by one not possessing special skill.

5 As a further improvement in holding devices of the character described the free end of the clamping-plate C³ thereof is shown as bent outwardly to form a lip C⁴. The object of this feature of construction is to insure a 10 perfect contact between the fuse-wire and said contact-plate adjacent to and outside of the point at which the fuse-wire is clamped. In the practical use of constructions wherein the opposite ends of a fuse-wire are clamped 15 between two clamping-surfaces which are in the circuit of the line-wire I have found that if said wire does not have perfect contact with the holding device outside of the point at which the ends are clamped therein and a 20 current sufficient to fuse the wire be thrown thereon an arc will be formed between the divided ends of the fuse-wire up to their points of attachment with the holding devices and between the coacting parts thereof, with 25 the result that the wire will be melted and the clamping parts soldered together by the resulting molten metal. When an excessive current is thrown upon the wire, the contact-faces of the clamping devices have been 30 known to become fused together, so as to render the device wholly inoperative. By forming the lip C⁴ upon the free end of the over-hanging part C³ it will be apparent that when 35 the end of the wire is clamped in place that portion thereof adjacent to the lip will be held tightly against or in contact with said lip and a perfect contact between the wire and said part of the wire is thereby insured. With this construction it will be apparent 40 that said wire will not fuse inside of its point of contact with the lip C⁴ for the reason that said wire will be relieved of its excess of current by the said lip and holding device C³ with the result of preventing possibility of 45 fusion in its part which is held between the opposing parts or jaws of the clamp.

The plug is provided upon its outer face with a raised or elevated portion A¹, located at the central part thereof, but terminating 50 at some distance from the margin or periphery of the plug, so as to form an angular recess or rabbet A², adapted to receive the main portion of the fuse-wire D, which extends between the clamping or holding devices C C. Said holding devices are located near each 55 other at one side of the plug, and the elevated part A¹ referred to is provided with adjacent marginal recesses in which the holding devices are located, but is at the same time extended between the said recesses in the form of a narrow projection A⁴, said projection being interposed between the holding devices, and thereby serving to avoid the possibility of short-circuiting between the same. The 60 raised portion A¹ and projection A⁴ thereof will preferably be made integral with the body of the insulating material forming the

70 plug and will have a flat outer face adapted to be engaged by the inner surface of the cap or cover A² when the latter is in position upon the plug, so as to limit the inward movement of said cover. The fuse-wire will be drawn or extended from one holding device to the other around the margin of the elevated part A¹, which by reason of its shape will maintain in place and in distended condition a 75 fuse-wire of considerable length.

The special arrangement of the parts described—namely, with the holding devices near each other at one side of the plug and 80 separated only by the narrow projection A⁴—obviously affords a maximum length in the groove or rabbet around the margin of the projection, in which the fuse-wire is confined or held and therefore enables a fuse-wire of 85 maximum length to be employed in connection with a plug of usual size.

The general advantage of the arrangement described is that it affords a long space for the fuse-wire between the holding devices, and 90 thereby makes it possible to employ a fuse-wire of considerable length, it having been found that better and more uniform results are obtained by the use of a long wire. Obviously the employment of a long wire and 95 the separation of the holding devices to a considerable extent will render short-circuiting through the air between the holding devices less likely to occur.

I claim as my invention—

1. The combination with a block provided with a socket and with insulated terminals therein, of a fuse-plug comprising a cylindric body of insulating material provided with a reduced end portion adapted to engage said 105 socket in the block, said plug being provided with two recesses to receive clamping devices, clamping devices located within said recess for detachably holding the opposite ends of a fuse-wire, means for fastening said clamping devices within said recesses comprising securing-screws which are inserted through apertures in the body of the plug and engaged at their inner ends with said clamping devices, and contact-pieces secured to the outer 115 surface of the plug and connected with the clamping devices by conductors extending through passages in the body of said plug.

2. The combination with a base provided with a socket and with insulating terminals 120 therein, one of which consists of a screw-threaded ring, of a fuse-plug comprising a solid cylindric body of insulating material provided with a reduced end portion, said plug being provided on its outer end with 125 two separate outwardly-opening recesses which are closed at their inner ends, two clamping devices for clamping the opposite ends of a fuse-wire which are located and closely-fitted within said recesses, a metallic 130 sheath surrounding said recessed portion of the block and exteriorly screw-threaded to engage said screw-threaded ring, and a contact-plate located centrally of the lower end

of said reduced portion which engages the other terminal, one of said clamping devices being provided with a conducting-strip which extends through a passage in the body of the 5 block to the said contact-plate and the other clamping device being provided with a short conducting-strip which extends through a second passage in the body of said plug to the outer edge of said screw-threaded sheath.

10 3. The combination with two clamping parts in a fuse-plug for electrical circuits, one of which is provided outside of its coating surface with a raised lip or projection, of a wire which passes transversely over said 15 lip in binding contact therewith and is clamped at its end between coating surfaces of said parts.

4. A fuse-plug for electric circuit comprising a solid cylindric body of insulated material provided with a reduced inner end portion, said plug being provided in its outer 20 end adjacent to one side with two clamping devices adapted to hold the opposite ends of

a fuse-wire, a metallic sheath surrounding said reduced portion and provided with exterior screw-threads, and a contact-plate located centrally of the inner end of said reduced portion, one of said clamping devices being provided with a conducting-strip which extends through an oblique passage in the 25 body of the plug and is connected with said contact-plate, and the other clamping device being provided with a short conducting-strip which is connected with the outer edge of said screw-threaded sheath, and the outer 30 end of the body being provided with a marginal rabbet adapted to receive the part of the fuse-wire between said clamping devices.

In testimony that I claim the foregoing as my invention I affix my signature, in presence of two witnesses, this 22d day of September, A.-D. 1897.

LESLIE C. ORRELL.
